UNITED STATES PATENT OFFICE

GEORGE C. FAIRBAIRN, OF PORT ARTHUR, TEXAS, ASSIGNOR TO THE TEXAS COMPANY,
OF NEW YORK, N. Y., A CORPORATION OF DELAWARE

INDICATOR

Application filed November 15, 1927. Serial No. 233,370.

This invention relates primarily to indicating mechanism and particularly to that type in which a signal or warning is given periodically to an attendant in charge of 5 certain apparatus to notify him of the need for carrying out some definite operation. The special purpose contemplated by the present invention is for the giving of an automatic signal either visible or audible to 10 designate the time for withdrawal of tar or other residue from each of a series of batteries of pressure stills.

It is commonly the practice to employ a single tar stripping unit in connection with 15 a group of batteries of stills ordinarily ranging between six and twelve batteries, each of which may consist of one or more stills. Usually it is necessary to draw off the tar or other residue from the bottom of the stills 20 of each battery at periodic intervals of from fifteen to twenty-five minutes. The withdrawal usually takes place under still pressure, although it may be below this pressure if desired and the residue is discharged into 25 an expansion chamber where the pressure is substantially released and additional vapors are driven off. Heretofore, there has been no effort made to regulate the periods for 30 withdrawal of residue or to avoid the simultaneous withdrawal from a plurality of batteries. This has frequently led to a condition in which the tar stripping unit is over-loaded by receiving the residue from several batteries at one time. An objectionable feature of this overloading of the tar stripping 35 unit is that its efficiency is greatly reduced by the increased pressure which is thus brought about. For most efficient operation, the unit should maintain a substantially uniform pressure which is very little above atmospheric. For the purpose of the present invention, it will not be necessary to enter 40 into a detailed description of the operation of the stripping unit since it is important only to understand its relation to the batteries of stills and the necessity or advantage of operating it under uniform conditions.

It is contemplated, by the present invention, to bring about the desired result by the 45 use of a special novel form of indicator which

will operate automatically to designate when each battery should discharge tar into the stripping unit. One of the problems encountered in this connection arises from the fact that the number of batteries of stills 55 in operation, and all of which discharge into the same tar stripping unit, may vary from time to time. For example, where twelve batteries are connected to the same unit, all twelve may be in operation at one 60 time, while at other times one or more of the batteries may be out of operation due to the necessity for cleaning and repairing them. In order to insure uniform conditions in the stripping unit regardless of the number of 65 batteries in operation, it is necessary to provide a very flexible timing device. It is therefore an important feature of the present invention to provide a simple and effective means for varying the number of equal 70 periods into which a given time interval may be divided. While the present invention is herein disclosed in connection with its application to a specific problem, it will be understood that it has a wide range of utility and 75 that the present disclosure is of an illustrative embodiment only.

One form of the invention will now be described in detail, with reference to the accompanying drawings in which:

Figure 1 is a perspective view of the apparatus as a whole.

Figure 2 is a plan view of a panel carrying a series of contact devices for controlling the operation of the signals.

Figure 3 is a sectional view along the line 3-3 of Figure 2.

Figure 4 is a plan view of the opposite side of the panel shown in Figure 2.

Figure 5 is a wiring diagram of connections from the contacts on the panel of Figure 2 to a series of jacks.

Figure 6 is a wiring diagram of connections from the panel and jacks to the several signaling devices.

Figure 7 is a view similar to Figure 4 but showing a modification.

Figure 8 shows diagrammatically the arrangement of a series of batteries of stills, a

common stripping unit and the individual indicators.

Referring now to Figure 1, there is shown a cabinet 1, which houses the main operative portions of the automatic timing device. The upper section of this cabinet is provided at its front with a panel board 2, carrying a series of jacks 3, somewhat after the fashion of a telephone switchboard. In an encased lower portion of the supporting structure, there is provided a series of electrical connectors 4, each having at its upper end a plug 5 adapted to be inserted in any one of the jacks 3. A cable 6, leading from the lower portion of the casing at any suitable point, carries a separate electrical connection from each one of the connectors 4. The cable 6 may be led to any suitable point where there may be located a large indicating device 7 having any desired number of separate compartments, twelve being shown. Each of the separate conductors in the cable 6 is connected to a different one of the compartments of the indicator 7 and serves to control a corresponding indicator in its related compartment. Any suitable form of indicator may be employed, but it preferably consists of an electric light which serves to make visible a large opaque numeral which is normally concealed behind a plate of frosted glass or other suitable translucent material. The indicator 7 will preferably be located at a point where it will be visible from any one of the batteries whose operation it is intended to control. Preferably there will also be provided in addition to the large indicator 7 a number of individual indicators 8 of similar construction, one for each battery of stills, A, B, C, etc. (Figure 8), these being located at any suitable point near each battery. Each of these second mentioned or auxiliary indicators will be connected in series or parallel with one of the compartments or sections of the indicator 7, so that each time one of the latter is illuminated, the corresponding auxiliary indicator will also be operated.

Figure 6 discloses diagrammatically the second or auxiliary set of indicators 8, which are connected by conductors 9 to the several sections of indicator 7. To complete the circuit, a connection 10 runs from each of the auxiliary indicators to the control unit in the casing 1, and a suitable source of current.

Returning now to the panel 2, it will be noted that the jacks 3 are arranged in a number of rows, the uppermost of which contains twelve jacks. The second row from the top contains eleven jacks; the next ten, etc., each lower row having one less than the one next above. There are seven rows shown so that the lowermost has six jacks. If desired, the number of rows could be increased or decreased, and the number of jacks in each row might vary from that shown, but the arrangement disclosed has been found very satisfac-

tory. The purpose of this arrangement is to permit of the use of any number of the batteries of stills without destroying the uniformity in the operating conditions of the connected tar stripping unit. Thus, when all twelve batteries are in operation, the plugs 5 will be inserted in the upper row of jacks 3, so that all twelve of the connectors 4 will carry the circuit from this upper row of jacks to the twelve sections of the indicator 7.

Now if one of the batteries should be taken out of operation for the purpose of cleaning or repairing it, the plugs 5 would be inserted in the second row of jacks 3, omitting the plug 5 which is related to the indicator designating the particular battery out of operation. Similarly, if only six of the batteries are in operation, the corresponding plugs 5 would be inserted into the jacks 3 of the lowermost row. It will rarely be the case that less than six of the batteries will be in operation at one time, but if this should happen to be a frequent occurrence, the number of rows of jacks could be increased correspondingly.

The mechanism whereby the circuits through the several series of jacks will be completed at periodic equal intervals of time for the purpose of successively operating the indicators 7 and 8 at uniform intervals, will now be described. Referring to Figures 2, 3 and 4, particularly, it will be noted that a panel 11 has secured thereto a series of contact elements 12 and 13, which are normally separated but are adapted to be brought together in the manner of closing a switch at their overlapping ends 14. If desired, platinum contact points may be provided on the elements 12 and 13. A plunger or button 15 secured at the point 14 to each contact element 12, passes through the panel 11 to the opposite side and extends into the path of an arm 16. This arm is secured to a shaft 17 which also passes through the panel 11 and is connected in any suitable way, by reduction gearing, to a driving means such as a synchronous motor 18 which serves as a timing device. The connection between these members is such that the arm 16 will make one complete revolution in a definite interval of time, which, in the present case, may most suitably be a period of twenty minutes. That side of the arm 16 which faces the panel 11, is preferably provided with a bevelled edge so as to readily cam the plungers or buttons 15 into the panel as the arm sweeps over these buttons, and if desired the upper ends of the buttons may either be bevelled or rounded. The arrangement of the elements 12 and 13 is such that those buttons 15 which are effective at any particular time, will be arranged at equal intervals about the circumference of the circle which they form. Thus, starting at the point 20 of Figure 4, there will be located a series of twelve buttons 15 at 30° intervals, and these, by the connections shown

75

80

85

90

95

100

105

110

115

120

125

130

diagrammatically in Figure 5, will be connected to the twelve jacks forming the upper row. Similarly starting from the point 20, there will be ten additional buttons 15 arranged at equal intervals so that the entire circumference will be divided into eleven equal parts. These buttons will then be suitably connected to the second row of jacks 3, as indicated in the diagram of Figure 5.

10 Actually the connection is between the jacks and the contact elements 12 rather than the buttons themselves but the explanation is simplified by referring to the buttons.

Another series of buttons 15 will similarly be provided to divide the circle formed by the buttons into ten equal parts, starting from the point 20, and these in turn, will be connected (as shown in Figure 5) to the third row of jacks 3. In the same way for each 20 row of jacks there will be a corresponding set of buttons 15 spaced at equal intervals from the starting point 20.

It will be apparent that some of the buttons 15 under the arrangement described, will 25 serve as a division point for several of the series of jacks. For example, the point 20 is common to all of the series and for this reason must be connected to the first jack of each of the rows. Similarly the button 21 will be 30 common to both the twelve and the six series of jacks, while the button 22 will be common to the twelve, ten, eight and six series. In each of these cases, therefore, the corresponding jacks in the panel 2 will be interconnected 35 and only a single connection will be necessary from one of these jacks to the common button 15. Other buttons common to several series will be apparent from Figure 5. In the diagram of this figure, the numbers within 40 the circle formed by the contact points, designate the group of jacks to which the adjacent contact points are connected; the upper group of jacks being known as the twelve group, and the lowermost being known as the six 45 group, while those in between are designated in accordance with the number of jacks in the row.

From the foregoing, it will be apparent that as the arm 16 moves at a uniform rate 50 over the buttons 15, it will tend to complete the circuit to the jacks of each series or row cyclicly and at equal intervals. For example, the jacks of the upper row will be successively rendered effective at intervals of 55 a little more than one and one-half minutes, while the jacks of the third row from the top will be successively rendered effective at intervals of two minutes and the lowermost series of jacks will be successively rendered 60 effective at intervals of something more than three minutes.

In Figure 6, there is shown a suitable arrangement of circuits for the entire signaling system when the upper set of twelve 65 jacks is employed. Alternating current from

a suitable source, such as designated 25 in this figure, may be adapted to operate a constant speed motor such as the synchronous motor 18 which serves to drive the arm 16 at a uniform rate. One terminal of the source of current may also be connected to the inner series 70 of contact elements 13, all of which are electrically interconnected by means of a conductor 27, as best shown in Figure 2. For simplicity of illustration, in the diagram

(Figure 6) this connection from the source of current has been shown as running to the pivot of the arm 16 which may then be assumed to be formed of some electrical conductor adapted to complete the circuit through the buttons 15 as it passes over them.

This form may be adopted as an alternative in the actual construction, if so desired. In the normal position of the parts,

as shown, a circuit will be complete through the button 20 which is connected to the first jack in the upper row, which, in turn, may be connected to one terminal of the lamp

80 forming a part of the signal 1. The connection 9 from the other terminal of this lamp may then be led to a terminal of the auxiliary indicator 1-a, constituting the signal at the first battery of stills.

From the other terminal of the indicator 1-a the connection

10 may serve to complete the circuit to the opposite terminal of the source of current 25.

A similar train of electrical connections will be combined to complete a circuit

100 through one of the sections of the indicator 7, and one of the auxiliary signals at a related battery each time the arm 16 passes over

one of the contacts 15 of the group of twelve that are spaced at 30° intervals. It will be

apparent that so long as the plugs 5 of the connectors 4 are inserted into the upper series of jacks, the passage of the arm 16 over

intermediate buttons 15 between those spaced at 30° intervals, will have no effect. Electrical

105 connections will be completed only up to the jacks of other rows under such conditions and will not be carried beyond to form a complete circuit.

110 In connection with the foregoing description, it has been found advisable to explain the mode of operation of the parts in fair detail so that it will not be necessary to enter

into a detailed description of the operation of the device as a whole but a very brief summary may be given as follows:

115 First of all, the plugs 5 related to the particular batteries of stills which are in operation, will be inserted in the jacks 3 of the row having a number corresponding to the

number of batteries in operation. For example, if nine of the twelve stills are operating at a particular time with #2, 6, and 8,

out of operation, the plugs related to batteries 1, 3, 4, 5, 7, 9, 10, 11, and 12, will be inserted in the nine jacks of the fourth row

120

125

130

from the top of the panel 2. A suitable switch in the circuit from the source of current will then be closed and will start the operation of the synchronous motor 18 to cause the arm 16 to be rotated at a uniform rate of—say one revolution in twenty minutes. As the arm passes over the buttons 15 of the series which are spaced at 40° intervals, circuits will be completed successively through the nine sections of the indicator 7 related to the plugs inserted, as well as through the nine auxiliary indicators located at the batteries themselves. In other words, under the conditions assumed, a different pair of signals will come into operation at successive time intervals of slightly over two minutes, and as soon as the signal at a particular battery is operated, the party in charge of the drawing off of tar from this battery will know that he should open the necessary valves to discharge the tar into the tar stripper. As soon as the desired amount has been drawn off, the valves will be closed and the system will await the operation of the next signal in order. By means of the main indicator 7, the attendant at any of the batteries may determine at any time how much longer he must wait for the next drawing off period. It will be apparent that either the main indicator or the group of auxiliary indicators alone would be sufficient to provide a satisfactory signal system, but both are preferred for complete information.

If it should be desired to indicate at the several batteries a particular allotment of time during which each battery is entitled to withdraw the tar bottoms, the arm 16 may assume the form of a sector 161, as shown in Figure 7, which preferably has an arc slightly less than the angular distance between the buttons 15 of the twelve series. In other words, this sector should be slightly under 30° so that operation of only one pair of signals at a given time will be assured. By the use of this construction, each pair of signals will remain in operation for a maximum period and will not be rendered ineffective until just prior to the operation of the next pair of signals in order. The sector might be of greater arc than 30° if desired, in order to give an indication of the duration of each period when one of the lower rows of jacks is employed. In this event, the period during which withdrawal of tar should take place may be measured by the time between the beginning of the operation of one section of indicator 7 and the operation of the next section. It will always be clear which of two sections of the indicator, that may be simultaneously operative, will designate the active battery, this being always the later one in the cycle. If the withdrawal of residue from each battery should require more than the allotted interval of time, the periods of withdrawal may be made

to overlap and if desired, the sector 161 may be of sufficient size to maintain the signal at each battery for a definite period of, say, three minutes, during which residue may be withdrawn. In actual operation, it may be found preferable to permit each battery to withdraw the tar bottoms in accordance with the requirements of the battery itself so long as the operation is begun at the proper time, but where it is feasible to do so, the use of the sector for arm 16 will tend to produce even greater uniformity in the operation of the tar stripping unit. Furthermore, with this form of contact member, the main indicator 7 will be substantially in continuous operation to designate the battery which is active in the cycle of tar drawing operations. While one admirable form of the invention has been disclosed in detail in the foregoing sections, it will be understood that many modifications may be made within the contemplation of the invention, as defined by the terms of the claims which follow. It has been mentioned that the motor 18 and connected gearing is preferably such as to give the arm 16 one revolution in 20 minutes. Obviously this speed may be made to suit any particular requirements and if desired provisions may be made for varying the speed at will within a reasonable range.

What I claim is:

1. In a device of the class described, a uniformly movable element, a series of contacts forming parts of electrical circuits and adapted to be controlled by said element to successively complete said circuits, a plurality of indicators, and means for placing any selected number of said indicators in said circuits so as to cause their successive operation at equal intervals of time, said means comprising a plurality of rows of jacks in said contact circuits, each of said rows having a different number of said jacks corresponding with the variable number of indicators to be operated and any row being rendered selectively effective.

2. In a device of the class described, a plurality of indicators, a series of contact devices, means for successively operating said contact devices in a continuous cycle, a plurality of rows of jacks, each row having a different number of jacks, connections from each jack of a row to one of said contact devices, said devices related to a row of jacks being operated at equal time intervals, and means for connecting any desired number of said indicators to the row having a corresponding number of jacks.

3. In a device of the class described, a series of electrical contacts arranged in a circle, a continuously and uniformly rotatable arm cooperating with said contacts, and adapted to successively close circuits through the latter, a plurality of indicators, and means for connecting any selected number of said indica-

tors to contacts equally spaced about said circle, said means comprising a plurality of rows of jacks, each row being separately effective and adapted for the selection of a different number of indicators.

4. In a device of the class described, a series of electrical contacts arranged in a circle, a plurality of rows of jacks each row having a different number of jacks, connections from the jacks of each row to a separate series of contacts equally spaced about said circle, a plurality of indicators, means for connecting any number of said indicators to the jacks of a row of corresponding number of jacks and a uniformly rotatable arm adapted to successively render said contacts effective.

5. In a device of the class described, a series of electrical contacts arranged in a circle, a plurality of horizontal rows of jacks each row having a different number of jacks, connections from the jacks of each row to contacts equally spaced about said circle, some of said jacks of different rows being connected to the same contact, a plurality of indicators, means for connecting any number of said indicators to the jacks of a row of corresponding number of jacks, and a uniformly rotatable arm adapted to successively render said contacts effective.

6. In a device of the class described a plurality of electrical indicators, a plurality of contact elements, a constantly and uniformly movable member co-operating with said contacts to successively provide electrical connections therethrough, a plurality of electrical connection-forming devices arranged in groups, the devices of each group being connected respectively with a separate corresponding series of equally spaced contact elements, and means constantly in circuit with said indicators adapted to be connected with any one selected group of said devices to predetermine the operation of said indicators.

7. In a device of the class described a plurality of electrical indicators, a plurality of contact elements, a constantly and uniformly movable member co-operating with said contacts to successively provide electrical connections therethrough, a plurality of electrical connection-forming devices arranged in groups, each group having a different number of said devices and the devices of each group being connected respectively with a separate corresponding series of equally spaced contact elements, and means constantly in circuit with said indicators adapted to connect a desired number of said indicators to a selected group having a corresponding number of said devices.

8. In witness whereof I have hereunto set my hand this 2nd day of Nov., 1927.

GEORGE C. FAIRBAIRN.
